United States Patent [19]

Carter et al.

[11] Patent Number: Des. 320,196

[45] Date of Patent: ** Sep. 24, 1991

[54] PORTABLE COMPUTER DOCKING STATION

[75] Inventors: **R. Richard Carter**, Cypress; **Thomas Mitchell**; **Douglas C. Bushman**, both of Houston, all of Tex.

[73] Assignee: **Compaq Computer Corporation**, Houston, Tex.

[**] Term: 14 Years

[21] Appl. No.: 258,972

[22] Filed: Oct. 17, 1988

[52] U.S. Cl. D14/107; D14/114

CLAIM

The ornamental design for the portable computer docking station, as shown and described.

DESCRIPTION

FIG. 1 is a top, front, right side, perspective view of a portable computer docking station showing our new design; a portable computer and its associated, detachable keyboard are shown in broken lines for illustrative purposes only and do not form a part of the claimed design;

FIG. 2 is a top, front, right side perspective view thereof without the portable computer;

FIG. 3 is a front elevation thereof;

FIG. 4 is a top plan view thereof;

FIG. 5 is a bottom plan view thereof;

FIG. 6 is a right side elevation thereof;

FIG. 7 is a left side elevation thereof; and,

FIG. 8 is a rear elevation thereof.

Fig. 1
